DOOR LATCH MECHANISM

George Janonis, Detroit, Mich.

Application July 7, 1941, Serial No. 401,360

9 Claims. (Cl. 292—223)

This invention relates generally to door latch mechanism and refers more particularly to vehicle door latch mechanism.

Ordinarily the doors of vehicle bodies are provided upon the inside and outside thereof with laterally projecting latch handles that not only constitute objectionable projections but also are unsightly and mar the appearance of the doors. In the present instance, I have overcome these objections and have otherwise improved the latch mechanism generally by eliminating the projecting handles so that the outside and inside of the doors are smooth and neat in appearance, and by employing handles that are normally out of the way and enhance rather than detract from the appearance of the doors.

Another object is to provide an improved latch bolt and keeper therefor which enables the latch mechanism to operate with a minimum of effort and are exceptionally effective to hold the door in partially or fully closed position.

Another object is to provide a latch mechanism that as a whole is simple in construction, inexpensive to manufacture, and easy to install.

Other objects, advantages and novel details of construction of this invention will be made more apparent as this description proceeds, especially when considered in connection with the accompanying drawings, wherein:

Figure 1 is an elevation of a door and jamb therefor when viewed from the outside of a vehicle body;

Figure 2 is a view similar to Figure 1 but showing the inside thereof;

Figure 3 is a view similar to Figure 1 with the outside panel of the door removed and showing latch mechanism embodying my invention applied to the inner panel and an upright of the door;

Figure 4 is a sectional view taken substantially on the line 4—4 of Figure 3;

Figure 5 is a sectional view taken on the line 5—5 of Figure 4;

Figure 6 is a sectional view taken on the line 6—6 of Figure 3;

Figure 7 is a sectional view taken on the line 7—7 of Figure 6;

Figure 8 is a sectional view taken on the line 8—8 of Figure 3;

Figure 9 is an edge elevation of the jamb.

Referring now to the drawings, A is a hinged or mounted door of a vehicle body, B is a jamb or upright abutment therefor, and C is the latch mechanism embodying my invention.

As shown, the door A has the inner and outer

panels 10 and 11, respectively, and the supporting uprights 12 and 13 to which said panels are rigidly secured. Preferably the inner panel 10 is covered with a suitable fabric trim panel 14. As usual, the door has a window opening 15 and is provided at the edges of said opening with suitable molding or finish strips 16. A vertically sliding glass panel or window 17 normally closes the opening 15 and is provided upon the opposed sides of the uprights 12 and 13 with runways or channels 18 in which the edges of the glass panel may travel. Any suitable mechanism (not shown) may be employed for sliding the glass panel 17 in the runways 18.

15 The jamb B is a rigid part of the vehicle body and limits the closing movement of the door A.

The latch mechanism C has a pivotally mounted latch bolt 19, a keeper or striker plate 20 therefor, and two remote control means 21 and 22, respectively, operable respectively from the inner and outer sides of the door for actuating the latch bolt 19.

As shown, the latch bolt 19 is wedge-shaped 25 in configuration and is mounted to swing over the outside of the free edge 23 of the door. Preferably the head 24 of the wedge-shaped bolt is rounded and has a laterally extending cylindrical shank 25 that extends through the free edge 23 of the door and is journaled in a bearing formed by complementary semi-circular portions 26 and 27, respectively, of case plate sections 28 and 29 upon the inside and rigid with the free edge 23 of the door. Such sections 28 and 29 are L-shape in cross section and are secured to each other as well as to the free edge 23 of the door. Preferably the webs 30 and 31, respectively, of said sections are secured together in back-to-back relation while the lateral flanges 32 and 33 of the sections are secured to the door.

The keeper 20 for the bolt 19 has a J-shaped portion 34 disposed edgewise on and rigid with an attaching plate 35 that in turn is rigid with 45 the jamb B, and is provided on the inner face of the J at the free edge of the shank 36 thereof with two steps 37 and 38, respectively, adapted to be successively engaged by the bolt 19. Preferably these steps 37 and 38 are integral and 50 are rigid with the J-shaped portion 34. In fact, the free end of the shank 36 is inclined so as to be flush with and form a part of the first step 37. Any suitable means such as the screws 39 may be used to secure the plate 35 to the jamb B.

55 The remote control means 21 and 22 are oper-

atively connected to the shank 25 of the bolt, preferably by pins 40 and 41, respectively, projecting from the shank at substantially diametrically opposite points thereof. Actually such pins 40 and 41 may be portions of one pin-like member that extends through the shank 25 or may be separate elements rigid with said shank. Extending in opposite directions from the pins 40 and 41 and connected to bolts 42 and 43 anchored in the webs 30 and 31 of the case plate sections are coil springs 44 and 45 that normally retain the tapered tail 46 of the latch bolt in lowered keeper-engaging position.

The remote control means 21 operable from the inner side of the door preferably comprises a relatively long lever 47 pivoted substantially midway its ends on a bracket 48 fixed to the inner panel 10 of the door and having one end portion 49 movable in a slot 50 in the case plate section 28 for engagement with the pin 40 on the latch bolt shank 25, a relatively short lever 51 also pivoted substantially midway its ends on the bracket 48 and having a pin 52 engaging a longitudinally extending slot 53 in the adjacent end of the long lever 47, a bell crank lever 54 pivoted at the juncture of the arms 55 and 56 thereof upon a plate 57 rigid with the inner panel 10 of the door, a long link 58 terminally connected to the short lever 51 and to the arm 55 of the bell crank lever 54, a hand lever 59 pivoted adjacent one end to lateral flanges 60 and 61 of the plate 57, and a short link 62 terminally connected to the hand lever 59 and arm 56 of the bell crank lever 54. Preferably the hand lever 59 is substantially T-shape in cross section. The upright flat portion 63 of the T is received within a recess or opening 64 in and is substantially flush with the outer surface of the molding 16 at the lower edge of the window opening 15 in the door, while the horizontal web 65 of the T is provided at one end with an inward projection 66 that receives the connection between the hand lever 59 and short link 62. As shown, this connection comprises a pivot pin 62' that is preferably an integral part of the short link 62 and that engages a hole 68 in the inward projection 66 of the web 65. It will also be noted that the plate 57 has an elongated slot 69 for receiving the web 65 and has an opening 70 at one end of said slot for receiving the adjacent end of the hand lever 59 during pivotal movement of the latter when the free end 71 of said lever is pulled outwardly from the recess 64 in the molding 16 to unlatch and open the door. Thus, by pulling outwardly the free end 71 of the hand lever 59, the bell crank lever 54, link 58 and levers 51 and 47 will cause the pin 40 to be depressed so that the latch bolt 19 will be retracted against the tension of the springs 44 and 45. In fact, the construction and arrangement is such that the springs 44 and 45 not only serve to hold the latch bolt 19 in its normally lowered position for engagement with the keeper 20, but also normally hold the hand lever 59 within the recess 64 in the molding 16. It should also be noted that the construction and arrangement of hand lever 59, molding 16 and trim panel 14 is such that the free end 71 of the hand lever 59 may be engaged by the fingers of the operator when it is desired to pull outwardly the free end 71 of the hand lever to unlatch and open the door and likewise the other end 72 of the hand lever 59 may be similarly engaged by the fingers when it is desired to pull the door from open to closed position. It will be noted further that

the engagement of the long lever 47 with the pin 40 on the bolt shank 25 is such that the bolt 19 is free to turn independently of the inside remote control means 21 when, for example, the door is slammed or pulled to closed position.

The remote control means 22 operable from the outer side of the door comprises an upright hand lever 73 disposed substantially parallel to and pivoted at its lower end upon an elongated bracket 74 rigid with the inside of the free edge 23 of the door, a substantially T-shaped pin 75 rigid with said hand lever below and slightly offset relative to the pivot 16 for said hand lever, and a long link 77 terminally connected to the T-shaped pin 75 and to the pin 41 on the shank 25 of the latch bolt 19. As shown, this link 77 has an elongated slot 78 receiving the pin 41 on the bolt shank so that the latter and pin 41 thereon may move independently of the outside control means 22 when the door is slammed or pushed to closed position, and has an opening 79 receiving the stem 80 of the T-shaped pin 75 on the hand lever 73. Preferably a fingerpiece 81 is provided on the outer side of the hand lever 73 at its upper free end to facilitate movement thereof by an operator. Thus, the construction and arrangement of the outer control means 22 is such that the springs 44 and 45 also normally hold the hand lever 73 in upright position substantially in registration with the elongated bracket 74 on the door. When the upper free end of the hand lever 73 is pulled outwardly, the link 77 will lift the pin 41 and thus cause the latch bolt to be retracted against the tension of the springs 44 and 45.

If desired, a dog 82 may be provided for rendering the hand lever 73 inoperative. As shown, this dog 82 is pivoted substantially midway its ends on the bracket 74 at the upper end thereof and has an end 83 engageable with a notch or recess 84 in the hand lever 73 to prevent the latter from being pulled outwardly as aforesaid to unlatch and open the door. Preferably the dog 82 would be operated from inside the vehicle body by a fingerpiece 85 projecting through the molding 16 at the upper edge of the window opening 15 and operatively connected to the other end 86 of the dog. Various different connections between the fingerpiece 85 and dog 82 may be employed, however, for the purpose of illustration, I have employed a flexible element or wire 87 connected to the end 86 of the dog 82 and extending upwardly in the upright 13 of the door to the upper edge of the window opening 15 where it is reeved over a pulley 88 in said upright and connected to the fingerpiece 85. Any suitable means such as a spring 89 may be employed for holding the fingerpiece 85 and flexible element 87 in an inoperative position so that the dog 82 is normally free of and disengaged from the hand lever 73.

Thus, from the foregoing, it will be apparent that I have provided an efficient latch mechanism wherein the operating handles or hand levers thereof are out of the way but readily accessible and that as a result, the inner and outer surfaces of the door are free of objectionable projections. All of the latch mechanism except the latch bolt 19 and keeper 20 are within the boundaries or confines of the door structure. Moreover, the construction and arrangement of the latch mechanism is such that the springs 44 and 45 hold both inside and outside remote control handles in their retracted out of the way positions and at the same time hold the latch

bolt 19 in its lowered keeper-engaging position, while permitting free movement of the latch bolt independently of both remote control means 21 and 22 when the door is slammed or pushed to closed position.

What I claim as my invention is:

1. In a door latch mechanism, a case plate, a latch bolt having a shank pivotally engaging the case plate and provided with a lateral projection, and actuating means for the latch bolt including a pivotally mounted lever engageable with the projection, an operating member at a point remote to the case plate, and an operating connection between the operating member and lever including a bell crank lever having one arm thereof operatively connected to the operating member, a lever having a slotted connection with the pivotally mounted lever, and a link extending between and connected to the last mentioned lever and to the other arm of the bell crank lever.

2. In a door latch mechanism, a case plate, a latch bolt having a shank pivotally engaging the case plate and provided with a lateral projection, and actuating means for the latch bolt including a pivotally mounted lever engageable with the projection, a hand lever at a point remote to the case plate, and an operating connection between the hand lever and pivotally mounted lever including a bell crank lever having one arm thereof operatively connected to the hand lever, a lever having a slotted connection with the pivotally mounted lever, and a link extending between and connected to the last mentioned lever and to the other arm of the bell crank lever.

3. A door latch mechanism comprising a case plate, a latch bolt having a substantially cylindrical shank pivotally mounted in said case plate, pins projecting from said shank at substantially diametrically opposite points thereof, oppositely extending springs terminally connected to said pins and case plate for holding the latch bolt in a predetermined position, and actuating means for the latch bolt including a pivotally mounted lever free of but engageable with one of the pins aforesaid, and a longitudinally movable link having an elongated slot receiving the other of said pins.

4. A door latch mechanism comprising a latch bolt having a pivotally mounted substantially cylindrical shank provided with a lateral projection, and actuating means for the latch bolt including a pivotally mounted lever free of but engageable with said projection, said lever having an elongated slot therein, an operating member at a point remote to the latch bolt, a bell crank lever having an arm operatively connected to the operating member, a lever having a pin movable lengthwise in the slot in the pivotally mounted lever,

and a link extending between and connected to the last mentioned lever and to another arm of the bell crank lever.

5. A door latch mechanism comprising a latch bolt, a bracket remote to the latch bolt, actuating means for the bolt including a hand lever pivoted on the bracket, and means for rendering the actuating means inoperative including a dog also mounted on the bracket and engageable with the hand lever, an operating member for the dog remote to the bracket, and a flexible connection between the operating member and dog.

6. A door latch mechanism comprising a pivotally mounted latch bolt provided with a projection, a pivotally mounted lever engageable with said projection to actuate the bolt, said lever having an elongated slot therein, an operating member, and an operating connection between said operating member and lever including a bell crank lever having an arm operatively connected to the operating member, a lever having a pin movable lengthwise in the slot in the pivotally mounted lever, and a link extending between and connected to the last mentioned lever and to another arm of said bell crank lever.

7. A door latch mechanism comprising a latch bolt provided with a projection, a pivotally mounted lever engageable with said projection to actuate the bolt, an operating member, and an operating connection between said operating member and lever including a bell crank lever having an arm operatively connected to the operating member, a lever operatively connected to the pivotally mounted lever, and a link extending between and connected to the last mentioned lever and to another arm of said bell crank lever.

8. A door latch mechanism comprising a latch bolt, means including a pivotally mounted lever for actuating the bolt, an operating member, and an operating connection between said operating member and lever including a bell crank lever having an arm operatively connected to the operating member, a lever operatively connected to the pivotally mounted lever, and a link extending between and connected to the last mentioned lever and to another arm of said bell crank lever.

9. A door latch mechanism comprising a latch bolt provided with a projection, a pivotally mounted lever engageable with said projection to actuate the bolt, an operating member, and an operating connection between said operating member and lever including a bell crank lever having an arm operatively connected to the operating member, a lever operatively connected to the pivotally mounted lever, and an operating connection between the last mentioned lever and another arm of said bell crank lever.

GEORGE JANONIS.
